APPARATUS FOR SCRUBBING AND
TREATING GRAVEL

William H. Allswede, Hersey, Mich.

Application August 1, 1930, Serial No. 472,376

6 Claims. (Cl. 209—6)

This invention relates to an improved apparatus for scrubbing and treating gravel to eliminate clay, rotten stone and the like.

The objects of the invention are:

- 5 First, to eliminate clay and rotten stone and the like from gravel.
- Second, to provide an improved scrubbing means for that purpose.
- Third, to provide an improved ball mill for

10 Objects pertaining to details and economies of construction and operation will appear from the description to follow.

A preferred embodiment of the invention is 15 illustrated in the accompanying drawings, in which:

Fig. 1 is a detail elevation view partially in section on line 1—1 of Figs. 2, 3 and 4.

Fig. 2 is an enlarged rear end elevation taken 20 from the left hand of Fig. 1.

Fig. 3 is an enlarged detail cross sectional view on line 3—3 of Fig. 1, showing details of the tumbling barrel means.

Fig. 4 is a similar detail cross sectional view 25 on section line 4—4 of Fig. 1, through the gravel rinsing screen part.

Fig. 5 is a detail perspective view of one of the liner sections.

Fig. 6 is a detail sectional view on line 6—6 30 of Fig. 5 showing details of construction.

The parts will be identified by their numerals of reference which are the same in all the views.

1 is a cylindrical drum of the ball mill barrel, 35 preferably 48 to 72 inches in diameter and of corresponding length as illustrated. In practice it is supported at an inclination of one and one-half inches to the foot, the higher end being the feed end and the lower end being the discharge end. 2 is a cylindrical gravel rinsing and

40 grading screen of like diameter to the said drum 1, secured to the discharge end thereof for screening the gravel after it has been scrubbed. It contains appropriate screen slots to secure the grade and size of gravel required. 3 are bearing rings which surround the said barrel 1 at suitable intervals to adequately support the same, two being shown in the structure. These are supported on pairs of rollers 4, the rollers on each side being carried on shafts 41 which are

45 supported in suitable bearings 42, 43 on a base 50 55. Gear ring 6 is provided at a convenient point along the length of the drum 1 to drive the same by suitable pinion in a well known manner. The pinion and driving means are not shown, as my invention does not pertain thereto.

The feed end of my improved drum is closed by the plate 7 which has a central circular opening 71 for the intake of material. The interior of the barrel is divided into compartments by plate rings 8, seen particularly in Fig. 1, a plate 60 being shown at the extreme end of the said drum. To these plates 8 are secured conical scrubbing screens 9 of about the proportion shown, which conical screens contain round holes one and three-fourths inches in diameter or larger so as 65 to pass the material to be scrubbed, and about one-half inch apart. The gravel introduced is screened for size in that all large pieces are eliminated. The inner ends of the screens 9 are closed by removable caps 91 to facilitate repair 70 and to permit of the introduction of the steel balls 92. Each compartment of the drum is lined with steel plates 10 which carry inch square longitudinal bars 11 which are riveted thereto, said lining being detachably secured so that it 75 can be readily renewed when worn.

Within the compartment I place a quantity of steel balls 92 of such size that they will not pass through the apertures in the screens 9. These balls in practice are steel about two to four inches 80 in diameter. Of course, cast iron balls or round stones might be used.

In operation the perforated water pipe 13 connected to a supply 14 delivers water to the rinsing and grading screen 2. My improved mill is very 85 effective if but a single length of scrubber with the rinsing and grading screen is provided. However, its action is greatly enhanced by a plurality and in practice I have used four ordinarily, as illustrated in the drawings. In the operation, 90 gravel, containing impurities such as clay and rotten stone and other hard stratified material, is introduced into the drum at 71 by any suitable means, as by chute or belt conveyor. A quantity 95 of water is introduced at the same time by hose or otherwise, enough to reduce the mass to a muddy consistency. The machine is then 100 revolved, all tendency of the material to stratify in the drum being obviated by the agitating bars 11 which carry the material and the steel balls 105 together up at the side and permit them to tumble down with a crushing action which quickly disintegrates all clay and rotten stone or like impurities within the mass of gravel but does not 110 in any way grind the gravel. It is not the intent to grind the gravel.

As soon as the machine is started, a continuous supply of the gravelly material to be treated is fed into the drum with the necessary water to secure 115

the muddy consistency and the action, the same being continuous after the start.

Owing to the incline of the drum this muddy material with the tumbling balls passes up into the conical screen 9 and then, owing to the large size of the perforations therein, the material is at once passed and crushed through to the next compartment where the operation is repeated and is repeated a sufficient number of times to disintegrate the rotten stone or clay.

When this is accomplished the whole mass of the material is discharged onto the gravel rinsing and grading screen 2 where the rinsing takes place. The disintegrated clay and rotten stone is at once washed away and the gravel is passed to a suitable bin or other point of discharge completely prepared for use and all objectionable material removed.

Having thus described my invention what I claim as new and desire to secure by Letters Patent is:

1. In an apparatus for scrubbing and treating gravel, the combination of a tumbling barrel ball mill crusher and grader of cylindrical form, a cylindrical gravel grading screen attached to the end thereof, partition rings for the said barrel dividing the same into compartments, conical scrubbing screens connected to the said partition rings and pointing forwardly, containing apertures larger than the size of gravel to be scrubbed and screened, liner plates for the said drum compartments having longitudinal agitator bars secured thereto, and tumbling balls of such size as not to pass the said scrubbing screens adapted to tumble in said compartments and roll up into said screens to crush defective material so that it may be discharged.

2. In an apparatus for scrubbing and treating gravel, the combination of a tumbling barrel ball mill crusher and grader of cylindrical form, a cylindrical gravel grading screen attached to the end thereof, a partition ring for the said barrel, a conical scrubbing screen connected to the said partition ring and pointing forwardly, containing apertures larger than the size of gravel to be scrubbed and screened, a liner plate for the said drum having longitudinal agitator bars secured thereto, and tumbling balls of such size as not to pass the said scrubbing screen adapted to tumble

in said barrel and roll up into said screen to crush defective material so that it may be discharged.

3. In an apparatus for scrubbing and treating gravel, the combination of a tumbling barrel ball mill crusher and grader of cylindrical form, a cylindrical gravel grading screen attached to the end thereof, partition rings for the said barrel dividing the same into compartments, conical scrubbing screens connected to the said partition rings and pointing forwardly, containing apertures larger than the size of gravel to be scrubbed and screened, liner plates for the said drum compartments, and tumbling balls of such size as not to pass the said scrubbing screens adapted to tumble in said compartments and roll up into said screens to crush defective material so that it may be discharged.

4. In an apparatus for scrubbing and treating gravel the combination of a tumbling barrel ball mill crusher and grader of cylindrical form, a cylindrical gravel grading screen attached to the end thereof, a partition ring for the said barrel, a conical scrubbing screen connected to the said partition ring and pointing forwardly, containing apertures larger than the size of gravel to be scrubbed and screened, a liner plate for the said drum, and tumbling balls of such size as not to pass the said scrubbing screen adapted to tumble in said barrel and roll up into said screen to crush defective material so that it may be discharged.

5. A tumbling barrel mill having a conical scrubbing screen and partition having apertures in excess of the size of gravel to be screened and having tumbling bodies of larger diameter than said apertures adapted to tumble in said barrel and roll up into said screen to crush defective material so that it may be discharged.

6. A tumbling barrel mill having a conical scrubbing screen and partition having apertures in excess of the size of gravel to be screened and having tumbling bodies of larger diameter than said apertures adapted to tumble in said barrel and roll up into said screen to crush defective material so that it may be discharged, and a gravel grader and screen attached thereto.
